UNITED STATES PATENT OFFICE.

MORRIS ROSSEIN, OF BROOKLYN, NEW YORK.

DESIGN FOR A RING.

57,728.

Specification for Design. Patented Apr. 26, 1921.

Application filed September 20, 1920. Serial No. 411,670. Term of patent 14 years.

To all whom it may concern:

Be it known that I, MORRIS ROSSEIN, a citizen of the United States, and a resident of the city of New York, borough of Brooklyn, county of Kings, and State of New York, have invented a new, original, and ornamental Design for a Ring, of which the following is a specification, reference being had to the accompanying drawing, forming part thereof.

The figure is a plan view of a ring, showing my new design.

I claim:

The ornamental design for a ring, as shown.

MORRIS ROSSEIN.
